COMBINED BOAT TRAILER AND CAMPER

Frederic L. Cox, Grifton, N.C.

Filed June 4, 1962, Ser. No. 70,413

Term of patent 14 years

(Cl. D14—3)

FIG. 3.

FIG. 4.

FIG. 1 is a perspective view of a combined boat trailer and camper, showing my new design in collapsed position;

FIG. 2 is a front perspective view in raised position;

FIG. 3 is a perspective view taken diagonally opposite FIG. 2; and

FIG. 4 is a side elevational view of FIG. 2 with the tongue broken away for convenience of illustration.

The dominant features of my design reside in the portions shown in full lines.

I claim:

The ornamental design for a combined boat trailer and camper, as shown and described.
